CHARLES MACKENZIE ABERCROMBIE, OF BRIDGEPORT, CONNECTICUT,
ASSIGNOR TO WHEELER & WILSON MANUFACTURING COMPANY, OF
BRIDGEPORT, CONNECTICUT, A CORPORATION OF CONNECTICUT.

NEEDLE-MOTION FOR SEWING-MACHINES.

No. 828,294.

Specification of Letters Patent.

Patented Aug. 14, 1906.

Application filed June 21, 1905. Serial No. 266,305.

To all whom it may concern.

Be it known that I, CHARLES MACKENZIE ABERCROMBIE, a citizen of the United States, residing at Bridgeport, in the county of Fairfield and State of Connecticut, have invented a certain new and useful Improvement in Needle - Motions for Sewing - Machines, of which the following is a full, clear, and exact description.

This invention relates to that class of sewing-machines in which the needle is given lateral movements transverse to the feed of the material, as in the ordinary zigzag, hem-stitch, and variety-stitch sewing-machines.

The invention consists of a reciprocating needle-bar provided with a vibrating needle-carrier and means to positively control and guide its vibration, such means including a guide-rod fixed to the needle-carrier by one end and rising therefrom and having a sliding connection with a sleeve which is swiveled in an arm or crank pivoted on the head of the machine, the swivel-sleeve being connected by a rod with a rotary cam driven from some moving part of the machine, such as the needle-actuating shaft, whereby the needle is positively vibrated in both directions, and therefore may be run at high speed without danger of cramping.

The invention is shown and described in connection with the Wheeler & Wilson hem-stitch sewing-machine as an illustration and without thereby limiting its applicability and scope.

In the accompanying drawings, illustrating the invention, in the several figures of which like parts are similarly designated, Figure 1 is a front elevation, the face-plate removed, the arm broken away in part, and the frame shown partly in section and partly in dotted lines. Fig. 2 is a front end elevation, the bed-plate being shown in cross-section alongside of the feed. Fig. 3 is a vertical sectional elevation of parts of the needle-carrier vibrating mechanism. Fig. 4 is a perspective view of the needle-carrier detached. Fig. 5 is a partly-sectional elevation of the needle-carrier and cross-head looking toward the left, Fig. 1.

Parts shown and not particularly described may be of the construction herein illustrated or of any other approved form, it being understood that, as usual, the cloth-feeding

mechanism is capable of imparting two forward-feed movements to the material alternating with one backward-feed movement, that the needle is moved laterally to place two stitches off the hem fold and one on, and that a piercer is provided to enlarge the off-hem needle punctures.

1 is the bed-plate; 2, the overhanging arm, in which is mounted the needle-actuating shaft 3, and 4 is the needle-bar mounted in the head 5 of the overhanging arm and connected through the needle-bar stud-collar 6, link 7, take-up cam 8, and take-up cam-stud 9 with the needle-actuating shaft 3.

10 is the needle-controlling cam connected with the needle-actuating shaft 3 through the bevel-gear 11, mounted on the needle-actuating shaft and meshing with suitable gear-teeth (not shown, but as usual) formed on the cam 10, the ratio of said gears being as three to one.

12 is a cross-head secured by screws 13 to the needle-bar.

14 is the needle-carrier, pivotally mounted upon the cross-head and secured by a screw 15. This needle-carrier is L-shaped, one arm 16 of which carries the needle 17, and the other arm 18 has secured to it by a screw 19 a guide-rod 20. This guide-rod passes through a swivel-sleeve 21, having a stud-shaft 22 journaled to rock in an oscillating crank 23, having a shaft 24 mounted in a suitable bearing 25 on the head 5, said shaft 24 being provided with a collar 26 to hold it against accidental longitudinal movement. The swivel-sleeve 21 is held against lengthwise movement by a suitable pin 27 engaging a groove in its stud-shaft 22.

28 is a connecting-rod, the end 29 of which encircles the stud-shaft 22 and its opposite end adjustably secured to a lever 30, mounted in a suitable bearing in the overhanging arm, the free end of said lever being provided with a roller 31, which tracks a groove 32, formed in the face of the cam 10, which cam-groove, through the connections 30, 28, 21, 20, and 14, transmits to the needle lateral movements in a manner to effect one stitch on the hem fold and two stitches off the hem fold.

A piercer 33 is secured by screws 34 to an adjustable bracket 35, secured by screw 36 to the cross-head 12, carried by the needle-

bar, such piercer actuated to puncture the material off the hem fold at every descent of of the needle.

The needle-actuating shaft 3 controls the vertical movements of the needle-bar 4, and the cam 10 controls the lateral movements of the needle 17 through the guide-rod 20, which is mounted to vibrate through an arc of a circle described from an independent fixed axis, 15 which in this instance is the crank-shaft 24, and this is a distinguishing feature of the invention.

The parts 21 to 24, both inclusive, act as a rest or bearing for the outer end of the connecting-rod 28, whereby it is held independent of the guide-rod 20 both as to movements vertically and horizontally in line with the seam, and hence the liability of the guide-rod to become cramped in the swivel-sleeve 21, 20 through which it passes, is practically eliminated.

What I claim is—

1. In a needle-motion for sewing-machines, a reciprocating needle-bar provided with a pivoted needle-carrier, a guide-rod fixed to said needle-carrier, an oscillating crank, a 25 sleeve swiveled in the free end of said crank and with which swivel-sleeve the guide-rod has a sliding connection, a rotary cam, and a connecting-rod between said cam and swivel-sleeve.

2. In a needle-motion for sewing-machines, a reciprocating needle-bar, a needle-carrier pivotally connected therewith, a guide-rod 30 fixed to said needle-carrier, a swivel-sleeve

through which said guide-rod slides as the needle-carrier is vibrated, an oscillating support in which said swivel-sleeve is mounted, a rotary cam, and a connecting-rod interposed between the cam and the oscillating 40 support for positively oscillating the support and thereby vibrating the needle-carrier.

3. In a needle-motion for sewing-machines, a needle-bar, a needle-actuating shaft and connections between said needle-bar and 45 shaft, a pivoted needle-carrier, a rotary cam, and connections between said cam and needle-carrier for positively vibrating said needle-carrier including a swivel-sleeve, an adjustably-mounted connecting-rod between 50 said swivel-sleeve and cam and a slideable connection between said sleeve and needle-carrier, said sleeve capable of rocking movement and a support in which said sleeve is mounted to rock, said support having an independent axial movement whereby the sleeve is adapted to oscillate in the arc of a circle. 55

4. The combination of a pivoted needle-carrier, a guide-rod fixed to it, a swivel-sleeve with which the guide-rod has slideable 60 connection, an oscillating crank in which the swivel-sleeve is mounted, and positively-acting means to vibrate the guide-rod with the axis of the crank as a center.

In testimony whereof I have hereunto set 65 my hand this 17th day of June, A. D. 1905.

CHARLES MACKENZIE ABERCROMBIE.
